UNITED STATES PATENT OFFICE.

HATTIE MAY PFALTZGRAFF, OF LAKewood, OHIO.

BUCKLE.

Application filed August 5, 1924. Serial No. 730,145.

This invention relates to buckles and particularly to those buckles which are adapted for use in holding two or more portions of straps together, such as are employed more particularly in connection with surgical appliances, including abdominal supporters, surgical corsets and the like, and which also may be used in connection with garters, suspenders and the like.

In the buckles now used in the construction of surgical appliances, including abdominal supporters, surgical corsets and the like, and in connection with suspenders, garters and the like, great difficulty is met by the wearer for the reason that the buckles do not hold securely, permitting slipping; they also become unfastened entirely and in most instances are uncomfortable to the wearer because of their length or because they materially increase the thickness of the articles of which they form a part.

The primary object of the present invention is to provide a buckle for such articles as are above mentioned which will (1) hold the parts of the straps securely, (2) prevent unfastening of the holding means and (3) cause a minimum increase in thickness of the supporting means at the buckle point.

Other and further objects will be apparent from a reading of the complete specification and claims.

Referring to the accompanying drawing wherein I have illustrated preferred embodiments of my invention.

Fig. 1 is a plan view of one form of my invention having a single clasp member.

Fig. 2 is an end view of Fig. 1.

Fig. 3 is a cross section on the line 3—3 of Fig. 1.

Fig. 4 is an elevational view of my invention as applied to a garter, the lower garter connection being illustrated in dotted lines.

Fig. 5 is a cross section on the line 5—5 of Fig. 4.

Fig. 6 is a view similar to Fig. 5 but showing two continuous straps being held in place.

Figs. 7 and 8 are respectively front and cross sectional views of my invention showing a modified use.

Fig. 9 is a front view of a modified form.

Figs. 10 and 11 are cross sectional views on the lines 10—10 and 11—11, respectively, of Fig. 9.

Fig. 12 is a modified form of my invention showing two clasp members.

Fig. 13 is a cross sectional view on the line 13—13 of Fig. 12.

Similar reference characters refer to the same parts in the several views of the drawing.

Referring particularly to Figs. 1 to 3.

The main body of the buckle comprises a back portion 20 having preferably two rectangular openings 21, 22, the former to cooperate with the fastening clamp, to be described, and the latter to be used as a loop, also to be described. At the sides of the back portion 20 are the sides 23, 24 which secure the front and back together. The sides are provided with pivoting bearing means 25, 26, respectively, to which are pivoted the clasp member 27. The pivoting bearings are formed by folding the portion of the front member adjacent the middle of the side, upwardly and over to form a cylindrical bearing.

Secured to the side portion 24 is a front member 28 which is connected to the side member 23 by interlocking lugs 29 on the side member 23 and 30 on the front member 28. This interlocking lug structure permits the making of the body portion of the buckle of sheet material while still providing a solid structure when the parts are assembled. The joint may be soldered if desired.

The clasp member 27 is provided at its outer end with snap members 31 which engage the outer edge of the front member 28 which latter is preferably rolled over as shown at 32 in Fig. 3. Below the pivots of, and integral with, the clasp member, is the strap gripping or engaging member 33. The lower edge of the strap engaging member 33 is located substantially below the axis of the pivots 25, 26 and consequently when the snap members 31 are engaged with the rolled over portions 32 of the top member 28, there will be no tendency of the parts to become loosened to release the straps which the buckle is intended to secure.

It is also to be noted that the strap engaging member presses the strap or straps between two edges 21^a and 21^b of the opening 21. The cross sections of the parts of the buckle are substantially all rectangular and consequently the holding edges are right angular. This feature is very important as the pressure from the edge of the engaging member 33 is counteracted by the pressure from the two edges 21^a and 21^b which

will hold the straps securely and prevent slipping but without cutting action.

In Figs. 4 and 5, I have illustrated one application of my invention to a garter. A strap of webbing or other suitable material is illustrated at 40. This strap passes in between the upper portion of the back member 20 and the clasp member 27. The strap 40 passes through the openings 21, 22, forming a loop around the solid portion 41 between the openings 21 and 22. Adjacent the sides of the front portion and outward of the lugs 42 are attached hooks 43 of stocking attaching means.

At the outer end of the clasp member 27 is an opening 44 to which another stocking attaching means 43 is secured. The lugs 42 prevent the stocking attaching means from coming under the clasp 27 and preventing its proper closing. It is obvious that the two outside or the center stocking attaching means may be omitted if desired.

In Fig. 6, I have illustrated a cross section of the form of my invention shown in Fig. 4 but having two strap members 40^a and 40^b extending between the clasp 27 and the back member, the strap engaging member 33 forcing the two straps together, the rear strap member 40^a being held securely against the edges 21^a, 21^b of the opening 21 and the front strap being held by the edge of the strap engaging member 33.

In Figs. 7 and 8 I have shown an arrangement with the loop of the strap 40 similar to Figs. 4 and 5 and having an additional sliding loop 45 extending over the lower bar at the bottom of the back member. The ends of this loop may be attached to garter fasteners, suspender fasteners or to any other desired fastening means. The operation of the clasp 27 is the same as in Figs. 4 and 5.

In Figs. 9, 10 and 11 I have illustrated a modified form of clasp showing a back member 120 having an opening 121. The rounded retaining portion 132 holds the snap members 131 in place. The snap members 131 are similar in construction to the parts 31 of Fig. 1 and form a part of the clasp 127 in a manner similar to the manner in which the clasp 27 and its snap members 31 are constructed. It will be noted that this form occupies much less space than the form previously described.

In Figs. 12 and 13, I have shown a form of my invention wherein a back member 220 is provided with two openings 221, 222. Two clasp members 227 are pivoted on the front member as shown and in position to force the strap or straps against the edges of the respective openings 221, 222. The other corresponding parts are similar to similar parts in the previously described forms and will not again be repeated.

In my structures, the placing of the strap gripping or engaging means, as at 33, 133

and 233, substantially below the respective pivot points, delivers a maximum amount of pressure without exerting a strain upon any fastening means of the clamping member, thus making it easy to hold the clamping member. The pressure of the strap engaging member being exerted between the two angular edges of the opening, causes a gripping action with these edges. These features with the snap members for holding the clasp member in place, render the holding action certain.

It will be clear from the above description, taken in connection with the drawings, that I have provided a buckle which will hold the straps securely, will have no tendency to become loose and at the same time will have a minimum thickness and no unnecessary projecting portions and will be cheap of manufacture.

While I have illustrated and described preferred embodiments of my invention I desire to have it understood that I do not limit myself to the exact showing and that modifications and changes may be made without departing from the spirit of my invention and within the scope of the appended claims.

Having described my invention what I claim is:

1. A buckle having back, front and side portions, the front and back portions being rigid relative to the side portions to form a frame closed at the corners on the front, sides and rear but open at the top and bottom, the back portion being provided with an opening extending thereacross, a clasp member mounted in place opposite the back portion, spaced therefrom and intermediate the upper and lower extremities of the front portion and in position to have its tongue opposite the opening to force the strap into engagement with the opposite edges of the opening when the clasp member is placed in operative position and means for holding the clasp in operative position.

2. A buckle having back, front and side portions, the front and back portions being rigid relative to the side portions to form a frame closed at the corners on the front, sides and rear but open at top and bottom, the back portion being provided with an opening extending thereacross, a pivoted clasp member mounted in place opposite the back portion, spaced therefrom and intermediate the upper and lower extremities of the front portion and in position to have its tongue opposite the opening to force the strap into engagement with the opposite edges of the opening in the back portion when the clasp member is swung on its pivot into operative position and means for securing the outer end of the clasp to hold the same in operative position.

3. A buckle having back, front and side

portions, the front and back portions being rigid relative to the side portions to form a closed frame at the corners in the front, sides and rear, but open at the top and bottom, a pivoted clasp member mounted in place opposite the back portion, spaced therefrom and intermediate the upper and lower extremities of the front portion and having a strap engaging portion, the back having an opening opposite the strap engaging portion of the clasp and in position to have the strap pressed against its opposite sides by the strap engaging portion, the back being provided with an additional opening in position to pass a strap loop through both openings whereby the strap engaging portion may press one side of the loop against one side of the opening opposite the same and both parts of the loop against the other side.

4. A buckle having back, front and side portions, the front and back portions being rigid relative to the side portions to form a frame closed at the corners on the front, sides and rear but open at the ends, the back portion being provided with an opening extending thereacross and having opposite angular edges, a clasp member mounted in place opposite the back portion, spaced therefrom and intermediate the upper and lower extremities of the front portion and having a strap engaging portion opposite the opening in the back portion and in position

to force the strap into engagement with the angular edges of two opposite sides of the opening and snap means for holding the 35 clasp member in operative position.

5. A buckle having a back member and a front member and side members, the back, front and side members being rigid with each other to form a frame open at its ends but closed at the corners of its front, rear and sides, a pivoted clasp member having an engaging portion for securing a strap within the frame, means at each side of the front member for attachment of an auxiliary strap 45 portion and means for holding the two auxiliary strap portions in spaced relation when attached.

6. A buckle having front, back and side members, the back, front and side members 50 being rigid with each other to form a frame open at its ends but closed at the corners of its front, rear and sides, a pivoted clasp member having an engaging portion for securing a strap within the frame, means at 55 each side of the front member and in the clasp member for attachment of three auxiliary strap portions and means for holding the three auxiliary strap portions in spaced relation when attached.

In testimony whereof I hereunto affix my signature.

HATTIE MAY PFALTZGRAFF.

CERTIFICATE OF CORRECTION.

Patent No. 1,630,758.

Granted May 31, 1927, to

HATTIE MAY PFALTZGRAFF

It is hereby certified that error appears in the printed specification of the above numbered patent requiring correction as follows: Page 2, lines 127 to 129, claim 2, strike out the words "and means for securing the outer end of the clasp to hold the same in operative position"; and that the said Letters Patent should be read with these corrections therein that the same may conform to the record of the case in the Patent Office.

Signed and sealed this 21st day of June, A. D. 1927.

Seal.

M. J. MOORE,
Acting Commissioner of Patents.
